UNITED STATES PATENT OFFICE.

CHARLES J. PUFFER, OF AURORA, ILLINOIS, ASSIGNOR TO JOHN C. ROBERTS, OF PEORIA, ILLINOIS.

VAPOR-STOVE.

No. 886,403.

Specification of Letters Patent.

Patented Nov. 20, 1906.

Application filed July 6, 1904. Serial No. 215,545.

To all whom it may concern:

Be it known that I, CHARLES J. PUFFER, a citizen of the United States, residing at Aurora, in the county of Kane and State of Illinois, have invented certain new and useful Improvements in Vapor-Stoves; and I do hereby declare that the following is a full, clear, and exact description of the invention, which will enable others skilled in the art to 10 which it appertains to make and use the same.

This invention has reference to new and useful improvements in a vapor-stove.

The invention has for its object a portable vapor-stove made of minimum size and combining with the burner and generator a gasolene-tank, an air-tank, and pressure-pump, all supported in the same structure.

The invention has for its further object a burner, the gas - conduit leading thereto 20 formed of bifurcated sections, each section provided with a jet or single burner for the purpose of producing a subflame, and a generator disposed beneath the burner, passing between the sections of the gas-conduit to 25 adapt the subflame from the jets thereof to act upon the body of the generator.

A further object of the invention is a detachable self-adjusting needle-point for the controlling valve - stem, having wings be- 30 tween which is arranged grooves or channels for the passage of the gasolene and gasolene-vapor. The wings of the needle-point serve to guide the needle-point to the orifice in the generator-tube in which the regulating valve 35 is carried.

A further object of the invention is a generating-tube, a needle-point controlling valve-stem operating in the tube having a reduced threaded extension which is connected to the 40 main stem by a knuckle-joint, the threaded extension of the stem having screw connection with a feed-valve operating in the generating-tube to shut off against the gasolene, means being provided for locking the relation 45 of the feed-valve and controlling valve-stem.

The invention consists, further, in various details of construction to be hereinafter more specifically described, and pointed out in the drawings forming a part of this specification, 50 in which—

Figure 1 is a plan view of a gasolene-generating apparatus, showing my improved stove. Fig. 2 is a side elevation of Fig. 1. Fig. 3 is a detached elevation and section, enlarged over

Figs. 1 and 2, of the burner, the generator, 55 mixer, and gas-conduit. Fig. 4 is a detached elevation and section, same scale as Fig. 4, of a portion of the burner, gas-conduit, and generating-tube. Fig. 5 is a longitudinal section of the generating-tube, its regulating- 60 valve and feed-valve. Fig. 6 shows, enlarged, a section of the forward end of the generating-tube, needle-point, and regulating valve-stem. Fig. 7 is an end view in section of the generating-tube, showing the needle-point. 65 Fig. 8 is a detached section of the coupling for the generating-tube and regulating-valve. Fig. 9 is a detail in section of the head end of the generating-tube.

In the drawings, like numerals of reference 70 indicate corresponding parts throughout the figures.

The apparatus consists of the base-plate 1, and the casting 2, supported above the base and upon the same by means of the corner 75 posts or supports 3. The base may be of sheet-tin or sheet metal, while the top casting 2 may be of cast-iron or other suitable material, cast with the opening 4, and the grid 5, disposed above a burner, to be described. 80 The stove is divided into two separate compartments. In one is arranged the burner and generating devices, in the other the gasolene and compressed-air receptacles. The gasolene and compressed-air containing 85 receptacles are carried beneath the opening 4 and the burner beneath the grid 5.

The compartments are indicated as 6 and 7 and are separated by the partition 8, and 9 denotes a plate-covering for the opening 4 to 90 be placed above the gasolene and compressed-air containing receptacles, the same being supported upon the lips or lugs 10, cast with the top 2, as seen in the figures.

The gasolene-tank is indicated as 11, and 95 the air-tank as 12.

13 denotes a screw-cap, by means of which ingress may be had to the tank 11, while the air-tank is provided with a feed-valve 14, connected by a tube 15 with a suitable air-pump 16.

17 denotes a tube connecting the air-tank with the gasolene - tank in the usual way to provide pressure for the feed of the gasolene to the generator and burner, and 18 is a feed-tube for the gasolene from its tank to a generating apparatus, to be described.

The burner comprises the base-plate 19,

supported by studs 20 of the grid 5, to which the plate 19 is fastened, and the plate 19 is provided with the central tubular opening 21 and the annular depressed body portion 22, 5 forming the gas-chamber of the burner.

23 denotes a cap-plate and is the burner proper, being provided with the jets 24, which may be of any suitable construction. There is also provided a central opening 25, into 10 which the tubular portion 21 of the base projects and serves a purpose to be described.

26 denotes a sheet of foraminated metal, gauze, or other material located beneath the jets of the cap-plate to diffuse the gas and 15 spread it uniformly to the jets, as is apparent.

27 denotes a gas-conduit having the bifurcated extensions 28, which lead into and are attached to the burner, and each of the extensions 28 are provided with the laterally- 20 extended jets or burners 29, for the purpose of producing a subflame on the generator-tube, to be described, and the walls of the extensions 28 are lined with some suitable perforated material 30 to hold the pressure back 25 and prevent the entire flame of the burner passing out of the jets and diffuse it in such a way that only a flame sufficient to keep the generator hot escapes through these jets. Connected with the gas-conduit 27 is a mixer 30 31 for the volatile vapor and air, the open end of which is in close proximity to the end of the generator-tube 32, which lies beneath the burner, the opening 21 therethrough and between the jets 29, where the subflame is 35 produced for constantly heating the tube 32. The end of the tube passes through a shield 33, extending from the gas-conduit to the under side of the burner, and prevents the ignition of the volatile vapor as it issues from the 40 tube 32, which would be the case if the shield was not there, owing to the disposition of the subflame-jets, as described. The heat and also the flame from the jets of the gas-conduit while it acts on the generating-tube 45 also passes up through the openings 21 and 25 of the burner; so that it may be utilized, as well as the flame from the burner proper.

The generating-tube 32 has its forward end supported in the shield 33, its rear or outer 50 end screwed into a coupling 34, and the coupling, by means of a stud 35, is attached to a lip or extension 36 of the top plate 2. The coupling is further provided with a threaded tubular extension 37, with which the end of the tube 18 is so connected as to prevent leakage 55 at this point. The coupling is provided with portions in front and rear of its inlet 37, the forward end having attached thereto the tube 32, as shown in Fig. 5, and its opposite end 60 has the conical-shaped bore, as at 38, the remainder thereof threaded and the threaded portion engaged by a tubular feed-valve 39, which has a conical or tapered end 40 to coincide with the tapered or conical portion of 65 the coupling 34, and through the wall of the

coupling leading from the tubular inlet portion 37 to the tapered inner bore is an elongated tubular opening 41, for the passage of gasolene from the gasolene tank and tube 18 to the generating-tube. The disposition of 70 the opening 41 is such that the feed-valve 39 controls the ingress of the gasolene to the generator, as will be clearly seen in Fig. 5. The feed-valve is provided with the finger-wheel 42 to facilitate the closing and opening 75 of the feed-valve.

The controlling-valve is an elongated stem, (designated as 43,) disposed in the tube 32 somewhat as shown in Fig. 5 and is provided with the helical flange or screw-flange 44, 80 forming a helical channel 45 around the stem 43, between the inner wall of the tube and the body of the stem, the flange 44 engaging with the wall of the tube. The formation of the channel 45 is for the passage of the gasolene and insures it being kept in motion within the tube and provides for the discharge of all extraneous substance in the gasolene from the tube. At 46 a reduced threaded stem 47 is connected, by means of a knuckle-joint, with the end of the stem 43, the stem 47 extending through the coupling 34 and having a threaded engagement with the tubular feed-valve 39, the end of the stem 47 projecting beyond the wheel 42 and having 90 connected therewith the adjusting and locking nut 48. The end of the stem 47 is provided with a recess or notch 49 to adapt its longitudinal adjustment in the valve-stem 39 by the use of a screw-driver, and the nut 100 48 is for locking the relative positions of stem and feed-valve, as is apparent. The use of the knuckle-joint in the stem 43 permits the stem to wobble and adjust itself to any unevenness or irregularities in the longitudinal 105 line of its tube and parts and prevents binding either in its use or adjustment. Between the end of the stem 43, where the knuckle-joint is located, and at the end of the tube in the coupling I have provided a gauze packing or screen 50, which surrounds the stem 47 and is adapted to retard the movement of the gasolene to insure a uniform feed of the same to the mixer.

The stem 43 at its forward end is provided 115 with a needle-point adapted to coact with a discharge-orifice in the end of the tube 32. This needle-point (indicated as 51) is self-adjusting and detachable in the head end of the stem 43. The needle-point consists of 120 the tapered point 52, operating in a tapered orifice 53 of the tube 43, and the central body portion of the needle-point is provided with a series of radial wings or guides 54, between which is arranged longitudinal channels or 125 grooves 55, serving as aid-channels for the passage of gasolene or vapor fed through the channel 45 on the stem. The rear portion of the needle-point is carried through a tubular member or nut 56, adapted to have a screw 130

connection with an opening 57 in the head end of the stem 43, the rear portion of the needle-point being secured in the nut 56 by means of a screw 58, screwed into the extended portion of the needle-point, with its head engaging the end of the nut 56, as shown in the figures. That portion of the needle-point in the nut 56 is smaller in circumference than the bore of the member 56 and adapts the forward portion of the needle-point to wabble or have oscillatory movement in several directions, the object of which is to permit the point to have sufficient play to find the center of the orifice in the tube 32. It is to be also noted that in the manner of securing the needle-point to the stem rotary motion imparted to the stem will not be imparted to the needle-point, and thus there is obviated the making large or boring out of the discharge-orifice in the tube by reason of the working in and out of the needle-point, and thus insuring a perfect closure when the needle-point is in the orifice. The needle-point is capable of having longitudinal movement imparted to it, but not rotary motion. The head end of the tube 32 is provided with a socket or reduced tubular portion 59, communicating with the discharge-orifice thereof, and serves as a seat for the wings or blades 54 of the needle-point. In the adjustment of the stem 43 and its needle-point the wings in their engagement with the wall of the reduced portion 59 of the tube will serve as a guide for directing the point 52 of the needle centrally in the orifice 53 of the tube. This form of needle-point insures the gasolene or gasoline-vapor being discharged from the generating-tube in a straight line and not at an angle, as it is found in practice that if the gasolene or vapor in its discharge contacts with a metallic surface it chills it and destroys its good qualities and does not make a perfect mixture with the air and produces a poor quality of gas, which is to be avoided in this class of device.

To adjust the length of the stem 43 so that when the valve-stem 39 has closed the inlet-opening 41 the needle-point 52 will have also closed the orifice in the generating-tube. The stem 47, as has been indicated, will be adjusted in the member 39, when the nut 48 will be locked on the stem 47 against the wheel 42, and thus lock the relative positions of the two valves, all of which, it is believed, is understood. There is provided on the outer end of the coupling 34 and surrounding the controlling valve-stem 39 a packing-nut 61 and suitable packing, (indicated as 62.)

The arrangement of the apparatus with the partition or dividing-wall 8 is to protect the gasolene-can 11 from the extreme heat produced by the burner when in operation, sufficient air-space being left between the partition and the gasolene-can to keep it cool.

If it is desired to employ the within apparatus as a gas-generating device for lighting purposes, it will be found very serviceable. In this event the cap-plate 23 may or may not be used, and the construction of the outlet from the gas-conduit 27 may or may not be reduced in size and a gas-conducting pipe 60 substituted therefor (shown in dotted lines in Fig. 3 of the drawings) leading to one or more incandescent fixtures or other suitable lights. From the above it is obvious that other suitable changes may be made and details and modifications resorted to without affecting the principle and scope of the invention.

Having thus fully described my invention, what I claim, and desire to secure by Letters Patent of the United States, is—

1. In a device of the class described, the combination of a burner, a generating-tube 85 disposed beneath the burner, a mixer in proximity to the end of the generator, a gas-conduit leading from the mixer to the burner and provided between the mixer and the burner with vertically-extending bifurcated 90 portions having horizontally-extending jets disposed upon opposite sides of the generator and producing a subflame adapted to act upon the generator, substantially as specified.

2. In a device of the class described, the combination of a generating-tube having a discharge-orifice and the tubular portion 59, a stem operating in the tube, a needle-point having a diminished outer end adapted for closing the orifice in the tube, the body of the 100 needle-point having radial wings extending laterally beyond said diminished end between which are arranged grooves for the passage of gasolene or vapor and the laterally-extending wings of the needle-point fitting within said tubular portion 59 and adapted to guide the needle-point into the orifice of the tube, substantially as specified.

3. In combination with a generating-tube having the socket 59 and the discharge-orifice 53, of a stem operating in the tube, a needle-point having a detachable relation with the stem and adapted to coact with the orifice in the tube, the body of the needle-point provided with radial portions and coacting with the wall of the socket 59 for guiding the needle-point into the orifice of the tube, and channel-ways extending longitudinally between the radial portions serving as a passage for the gasolene or vapor, substantially as specified.

4. In a device of the class described, a coupling provided with an inlet into the body thereof, a generating-tube connected with the coupling and having a discharge-orifice, a 125 tubular feed-valve adapted for closing the inlet in the coupling, a controlling valve-stem operating in the tube, a detachable and non-rotating needle-point of the stem coacting with the orifice in the tube, a threaded exten- 130

sion of the stem adapted to have connection with the feed-valve and means for adjusting and locking the relative positions of the feed-valve and stem carrying the needle-point, substantially as specified.

5. In a device of the class described, the combination of a generating-tube provided with a discharge-orifice, a coupling to which the inner end of the tube is connected, the same provided with a feed-opening for feeding gasolene to the tube, a stem operating in the tube having a needle-point coacting with the orifice in the tube, a controlling valve-stem for controlling the feed-opening in the coupling, and a threaded extension having a knuckle-joint with the needle-point stem and an adjustable connection with the controlling valve-stem, substantially for the purposes specified.

10 6. In a device of the class described, the combination of a coupling having a longitudinal opening, a portion of the wall thereof being tapered and a transverse opening leading from the tapered portion of the coupling

15 to a suitable feed, a generating-tube attached to the coupling and provided with a discharge-orifice, a feed valve-stem operating in the coupling and having a tapered portion coacting with the tapered wall therein, an elongated feed valve-stem operating in the tube having a needle-point coacting with the discharge-orifice therein, a reduced stem having a knuckle-joint connection with the end of the main stem and adapted to have a threaded connection with the feed valve-stem, means for adjusting the relative position of the feed valve-stem and the needle-point stem, and suitable packing around the reduced stem between the main body of the coupling and the end of the main stem which carries the needle-point, substantially for the purposes specified.

20 In testimony whereof I affix my signature in presence of two witnesses.

CHARLES J. PUFFER.
